UNITED STATES PATENT OFFICE.

JACQUE L. MORGAN, OF KANSAS CITY, MISSOURI.

DESIGN FOR A SCOOTER.

49,395.

Specification for Design.

Patented July 18, 1916.

Application filed April 17, 1916. Serial No. 91,816. Term of patent 14 years.

To all whom it may concern:

Be it known that I, JACQUE L. MORGAN, a citizen of the United States, residing at Kansas City, Jackson county, State of Missouri, have invented a new, original, and ornamental Design for Scooters, of which the following is a specification, reference being had to the accompanying drawing, forming part thereof.

The figure is a perspective view of a scooter showing my new design.

I claim:

The ornamental design for a scooter, as shown.

JACQUE L. MORGAN.
